UNITED STATES PATENT OFFICE.

DELOS S. GILLESPIE, OF LOS ANGELES, CALIFORNIA, ASSIGNOR OF ONE-FOURTH TO
FRANCIS M. TOWNSEND AND FRANK L. A. GRAHAM, BOTH OF LOS ANGELES, CALI-
FORNIA.

KEY-HOLDER.

1,183,812.

Specification of Letters Patent. Patented May 16, 1916.

Application filed March 5, 1913. Serial No. 752,212.

To all whom it may concern:

Be it known that I, DELOS S. GILLESPIE, a citizen of the United States, residing at Los Angeles, in the county of Los Angeles and State of California, have invented a new and useful Key-Holder, of which the following is a specification.

My invention relates to a key holder of the general type known as key ring, and 10 the main object of my invention is to provide a key holder of the character described in which provision is made for segregating the keys carried thereon, and further in 15 constructing the holder so that the same is in convenient form for placing advertising matter thereon.

Another object of my invention is to provide a key holder of the class described of simple form and construction which may 20 be manufactured at a minimum cost.

Referring to the drawings, which are for 25 illustrative purposes only: Figure 1 is a perspective view of a key holder embodying the preferred form of my invention.

Fig. 2 is a transverse sectional view on line x^2-x^2 Fig. 1.

1 designates a thin metallic plate, although it is understood that the plate may be made of any substance having resilient 30 qualities. The plate 1 is provided at one end with a circular opening 2. The end of the plate 1, at the end provided with the opening, being substantially concentric to the opening therein, forms a circular 35 tongue 3.

In the form shown in the drawing, the metal of the plate 1, at one side of the opening 2, is slotted as indicated at 4, which slot extends from the edge of the plate 40 transversely of the plate into the opening 2. The plate 1 is also provided with a longitudinally extending slot 5 which extends rearwardly from the opening 2 into the plate 1 tangentially of the opening 2 and 45 parallel to one side of the plate. The portion of the plate 1 between the slot 5 and the side thereof forms a tongue 6 which may be sprung downwardly, as indicated in dot and dash lines in Fig. 1, or upwardly, if so desired. The end of the plate 1 forms substantially a curved tongue 3, the end of which is formed by the transverse slot 4 in the plate 1.

By forming the plate 1 in the manner 50 above described, it is readily understood

that two tongues are formed, the ends of which are approximately together, each of which is of considerable length so that the adjacent ends of the tongues 3 and 6 may be readily sprung apart for the purpose of 60 inserting keys or similar objects over the tongue 3.

7 designates a chain, one end of which is connected to the plate 1 through an opening 8. The opposite end of the chain is 65 provided with a ring 9 adapted to be placed on the tongue 3 of the plate.

The holder heretofore described is designed to be used in the following manner: The chain 7 being made, as shown, of 70 considerably greater length than the tongue 3 of the plate 1, a number of keys may be placed thereon by removing the ring 9 from the tongue 3 through the transverse slot 4 of the plate by springing either the end of 75

the tongue 3, or the end of the tongue 6, thereby disengaging the ring 9 from the plate 1. The ring 9 may then be passed through the opening in the key, it being understood that ordinarily keys are provided 80

with an opening in the handle end thereof, and after the keys have been placed on the chain 7, the ring 9 is again placed on the tongue 3 of the plate 1 through the transverse slot 4 thereof, as heretofore described. 85

If it is desired to segregate the keys, in order to have certain keys, which are mostly used, where they can be readily found, the same is accomplished by placing one or more keys directly on the tongue 3 of the plate 1, by inserting the same through the transverse slot 4 of the plate, by springing either the tongue 3 or the tongue 6. The plate 1 is preferably elongated, as shown, extending away from the key end of the 90 plate, so that the space away from the keys may be used, one side for an advertisement, and the other side, if desired, for the name and address of the owner of the key holder and keys. 95

What I claim is:—

A key holder comprising a flat plate, a tongue formed by cutting a circular hole through one end of said plate, said hole being large enough to receive the handles of a number of keys and said tongue being completely cut through near one of its intersections with the plate, a rectangular tongue formed on said plate adjacent to the cut on said circular tongue, and a chain 105 110

having one end secured in a small hole in said plate and having its other end attached to a small ring sliding on said circular tongue, said chain being sufficiently long to allow the handles of several keys to be linked thereon.

In testimony whereof, I have hereunto

set my hand at Los Angeles, California, this 21st day of February, 1913.

DELOS S. GILLESPIE.

In presence of—
FRED A. MANSFIELD,
ISABEL HALL.
